Primary Examiner — Catherine A Tuttle(74) *Attorney, Agent, or Firm* — Casey H. Kempner;
Siamak S. Hefazi(57) **CLAIM**

The ornamental design for a golf tee, as shown and described.

DESCRIPTION

FIG. 1 is a perspective view of a golf tee showing our new design;

FIG. 2 is a front view thereof, the back view, left view, and right view being the same as the front view;

FIG. 3 is a bottom view thereof; and,

FIG. 4 is a top view thereof.

The broken lines depict the portions of the golf tee that form no part of the claimed design.
